Attorney.

UNITED STATES PATENT OFFICE

JOHN ROBERT McFARLIN, OF PHILADELPHIA, PENNSYLVANIA, ASSIGNOR TO ELECTRIC SERVICE SUPPLIES COMPANY, OF PHILADELPHIA, PENNSYLVANIA, A CORPORATION OF PENNSYLVANIA

LIGHTNING ARRESTER

Application filed August 31, 1923. Serial No. 660,299.

My invention is a lightning arrester adapted for protecting electrical apparatus from lightning and other high voltage disturbances. It is designed to secure highly efficient protection from such disturbing charges by providing a discharge path therefor containing relatively little impediment to the passage of such charges while providing means for effectively interrupting the flow of dynamic or line current to ground following a discharge of high voltage current.

My improvements are particularly applicable to arresters having a discharge path for high voltage charges containing an impediment, such as one or more air gaps, sufficient to prevent the normal flow of dynamic or power current therethrough, but through which such dynamic or power current will continue flowing across the arc formed by the discharge of abnormal voltages. By my improvements, the line current (which maintains the arc after the discharge of the abnormal charge or current) is short circuited to extinguish the arc by the closing of a normally open path, which is automatically reopened as soon as the arc has been extinguished, and the flow of line current to ground is thereby interrupted. The closing of the normally open path is effected under control of current flowing in one of the several parallel conductors into which the discharge path is divided over a portion of its length, and the continuity of such discharge path conductors is not affected by the diversion of the current therefrom.

In the preferred embodiment of my invention, the discharge path contains a plurality of spaced electrodes forming an air gap or gaps; an electrode on the one side of a gap having connected therewith a shunt resistor and a coil connected across the ends of the resistor. The shunt resistor and coil may be connected to ground either directly or through a series resistor. The discharge path on the line side of the gap is connected with an electrode forming part of a normally open path, which is momentarily closed by an armature actuated by current flowing in the coil and when so closed forms a path to ground across the air gap, shunt resistor and

coil, the current flowing thereto being thus shortcircuited and the armature allowed to move out of contact with its coating electrode to interrupt the discharge of the line current.

While the escaping line current is preferably short circuited from the line side of the gap to effect the extinguishment thereof, and the apparatus for effecting such short-circuiting is preferably disposed on the ground side of the gap, it is to be understood that changes may be made in the relative arrangement of the parts without departing from my invention.

Such apparatus may be advantageously enveloped in a completely enclosed case by which it is protected from weather or tampering, the parts being so formed and arranged as to require no adjustment and very little replacement.

The following description and the accompanying drawing illustrate preferred embodiments of my invention, the characteristic features thereof being defined by the appended claims.

In the drawing, Fig. 1 is a vertical sectional view of a lightning arrester embodying my invention; Fig. 2 is a top plan view thereof, partly in section; Fig. 3 is a diagrammatic illustration of the electrical paths formed by the parts; and Fig. 4 is a diagrammatic illustration of a modified form of apparatus embodying my invention.

As illustrated in Figs. 1, 2 and 3 of the drawing, a hollow body 1, having an integral wall and bottom, is provided with a cover 2 adapted to be secured in place by the bayonet joints 3, the joint between the cover and body being sealed by cement. The casing thus formed is preferably made of glazed porcelain; the body being provided with the exterior lugs 4 and spaced ribs 5 for the engagement of a strap iron hanger 6.

A supporting conducting plate 7, engaged between the body and cover of the casing, is connected through the terminal 8 with a conductor 9 leading from a line wire or device to be protected. An electrode 10 has a threaded boss 11 projecting through an aperture in the plate 7, the electrode being held in firm en-

gagement with the plate by a nut 12 on the boss. A non-conducting tube 13 is sleeved on the electrode 10 and pinned thereto by a rivet 14.

5 The plate 7 has projecting therefrom spring clips 7' which engage the inner surface of the body 1 and serve to retain the plate 7 in fixed relation thereto. In contact with the plate 7 is a gap electrode 15 supported on the spool 16 and comprising a dished disc forming an annular rib 15'. A second gap electrode 17, comprising a dished disc forming an annular rib 17' is spaced and insulated from the electrode 15 by the insulating spool or collar 16 surrounding the upper end of the tube 13, the ribs 15' and 17' having between them an air gap 18 constituting a bar to the passage of line current excepting when an arc across the gap has been formed by a high voltage discharge.

20 The gap electrode 17 is supported upon the non-conducting end of a bobbin 19 on the tube 13, on which is wound a solenoid coil 20 connected with the gap electrode 17. The bobbin 19 is supported on the tube 13 by friction and by a tube 21 sleeved on the lower end thereof and pinned thereto by a rivet 22 passing through both tubes and through a bottom closure or plug 23.

25 A conducting bracket 24, clamped to the tube 21 by the clips 25, has riveted thereto the conducting sockets 26' and 27'. The socket 26' has a shunt resistor 26 secured therein by adjustment of the screw 26a, and the socket 27' has a series resistor 27 secured therein by the adjustment of the screw 27a. The shunt resistor 26 has secured to the bottom thereof a conducting band 26" provided with an adjusting screw 26b, and this band is connected by an insulated conductor 28 with the gap electrode 17. The end of the solenoid coil 20 is connected with the bracket 24 by means of a screw 25', so that the solenoid coil forms a shunt conductor to a portion of the discharge path across the terminals of the resistor 26.

30 The series resistor 27 has a conducting band 27" fixed upon the bottom thereof by the adjusting screw 27b and such band is connected with a ground wire 29 through the connector 30 and ground binding post members 30' and 30". The series resistor 27 serves to limit any flow of dynamic current to ground to a safe and moderate value; but on low voltage 350 circuits, such for example as those of 350 volts and under, the series resistor 27 may be omitted since the resistance in the ground connection, which may average about 25 ohms, will limit the dynamic current to a safe value.

35 A conducting armature 31 in the tube 13 has connected therewith a binding post 32 projecting through the axial slot 33 in the tube, the binding post 32 being connected by a flexible conductor 34 with the bracket 24 through the screw 25'. The armature rod 31

is normally held by gravity at the bottom of the tube 13 so as to maintain normally open the conducting path formed when this armature is elevated into engagement with the tube electrode 10.

40 In operation, a lightning discharge from line to ground enters the arrester through the lead line 9, passes through the plate 7 and electrode 15, jumps the air gap 18 formed between the ribs 15' and 17', and flows to ground through the connector 28, shunt resistor 26, bracket 24, series resistor 27, connector 30, ground binding post members 30' and 30" and ground conductor 29. This discharge path, containing only a small air gap 45 and low noninductive resistors, is highly efficient in discharging lightning. The lightning discharge does not flow through the highly inductive solenoid winding 20 but passes through the non-inductive resistor 26, while the higher ohmic resistance of the resistor 26 as compared with the winding 20 causes the dynamic or power current following the discharge to ground to flow largely through the winding 20, the continuity of which is not broken by the action of the short circuiting mechanism.

45 The ionization by a lightning discharge of the air in the gap 18 permits the dynamic or line current to maintain the arc between the electrode ribs 15' and 17' and follow the disruptive charge. Since, however, the shunt resistor 26 diverts this dynamic or line current through the solenoid coil 20, the latter attracts the armature 31 and elevates it into contact with the tube electrode 10. The line current is thereby diverted from the plate 7 through the electrode 10, armature 31, binding post 32, conductor 34, bracket 24, series resistor 27, connector 30, ground binding post 50 members 30' and 30" and conductor 29 to ground, thereby short circuiting and extinguishing the arc in the gap 18 and short circuiting and rendering inoperative the solenoid coil 20. The short circuiting of the solenoid coil 20 causes the fall of the armature 31 and breaks the circuit therethrough. Any arcing from the break takes place within the insulating tube 13 between the tube electrode 10 and armature 31 instead of between the gap electrodes, whereby the necessity for renewal of the gap elements or adjustment of the gap due to burning is practically eliminated.

55 It will be observed that the action is extremely simple, entirely automatic and positive and, as the lightning discharge itself does not at any time flow through the circuit breaker, the lightning discharge path to ground is fixed and uninterrupted. Neither the circuit breaker itself nor the position of the movable armature during operation has any effect whatever on the efficiency of the arrester in discharging lightning, single charges or multiple charges of any frequency.

being conducted to ground with equal efficiency.

It will be understood that additional air gaps may be interposed in the apparatus as, for instance, between the resistor 27 and the ground wire 29; or the gaps may be interposed in the discharge path at a point intermediate between line and ground members, and, as used in the claims, the term grounded member is intended to include not only a member having a direct connection with ground, but any member through which current flows on its way from the coil, resistors or armature to ground.

In the modification illustrated Fig. 4, the air gaps providing the impediment to normal discharge of dynamic current are interposed between the electromagnetic coil and series resistor (instead of between the line and the coil) and the coil and shunt resistor are connected with the line wire or other device to be protected. The parts may otherwise be similar to the parts shown in detail in the other figures. In the operation of this construction, a lightning discharge entering the arrester through the lead in wire, passes through the plate 7a, conductor 28a, shunt resistor 26a, bracket 24a, to gap electrode 15a, from the annular rib of which it leaps across the gap 18a to the annular rib of electrode 17a, thence through the electrode 15b (contacting with the electrode 17a), across the air gap 18b to the electrode 17b, and through series resistor 27a and conductor 30a to ground. The arcs formed across the air gaps by the disruptive discharge complete a path for the flow of dynamic or line current to ground. Such current is, however, diverted by the shunt resistor 26a through the electromagnetic coil 20a, connected with electrode 7a, and thereby causes the attraction of the conducting armature 31a which is elevated into contact with the electrode 10a, (electrically connected with plate 7a). As the armature is connected through the conductor 34a with electrode 17b, the engagement of the armature with the electrode 10a short-circuits the coil 20a and gaps 18a and 18b, thereby de-energizing the coil, extinguishing the arcs across gaps 18a and 18b, causing the armature to drop and ending the flow to ground of dynamic current.

Having described my invention, I claim:

1. A protective device comprising a conductor, a non-conducting tube containing an electrode connected with said conductor, spaced electrodes forming a spark gap, a resistor and a coil connected in parallel and to one of said spark gap electrodes, and an armature movable in said tube into contact with the electrode therein under control of current in said coil, said armature automatically disengaging from said electrode when there is no flow of current in said coil.

2. A protective device comprising a supporting conducting plate, an insulating tube depending from said plate, an electrode in said tube connected with said plate, spaced electrodes forming a spark gap, a solenoid 70 coil sleeved on said tube and connected with one of said electrodes, a resistor supported by said tube and connected with said last named electrode in parallel with said coil, and an armature reciprocable in said tube under control of current flowing in said coil.

3. A protective device comprising a hollow casing, a conducting plate supported in the upper part of said casing, an insulating tube depending from said plate and having 80 therein an electrode connected with said plate, spaced electrodes around said tube and forming an air gap, a coil around said tube and connected with one of said gap electrodes, a resistor supported by said tube and connected with one of said gap electrodes, and an armature movable in said tube under control of current flowing through said coil to engage and disengage said tube electrode. 85

In testimony whereof I have hereunto set 90 my hand, this 29th day of August, 1923.

JOHN ROBERT McFARLIN.
